UNITED STATES PATENT OFFICE.

DUNCAN MACDONALD, OF GARFIELD, OHIO.

BURNER FOR KEROSENE AND THE LIKE.

Application filed November 14, 1921. Serial No. 514,869.

To all whom it may concern:

Be it known that I, DUNCAN MACDONALD, citizen of the United States, and residing in the town of Garfield, in the county of Mahoning and State of Ohio, have invented or discovered a new, useful, and Improved Burner for Kerosene and the like, of which the following is a specification.

My invention consists in a new and improved burner for kerosene and the like.

While applicable to other uses, my improved burner is more particularly intended for use with steam-driven motor vehicles.

The object which I have in view is the provision of a burner which will possess an increased flame and heating capacity for a given area, which will provide for a uniform distribution of the fuel and therefore produce a uniform flame throughout its entire surface, which will not unduly expand or its efficiency become impaired by expansion, and which will not blow back into the gas chamber.

With these purposes in view, I have provided a burner whose flame surface is characterized by parallel series of gas slots, each series being multiple in character and adjacent series being separated by solid or unslotted portions which may be provided with a covering of asbestos or other refractory material. Thus I have shown, as the preferred form of my improved burner, the flame surface formed by a plurality of metal channels having their troughs filled with asbestos and spaced apart by means of spacer bars between which are formed the gas slots.

To provide the necessary flexibility to take up excess expansion, which might otherwise distort the burner surface and impair the efficiency of the burner, said spacer bars are assembled in staggered relation and their interlacing ends are pivotally connected together and to the flanges of the adjacent channels, the holes through which the pivot members pass fitting loosely enough to take up considerable expansion.

Other novel features of construction and

of arrangement of parts will appear from the following description.

In the accompanying drawings, which are, however, merely intended to illustrate a practical embodiment of the principles of my invention without limiting the scope of the latter to the construction shown, Fig. 1 is a top plan view of a burner constructed in accordance with the principles of my invention; Fig. 2 is a sectional view of the same taken along the line II-II in Fig. 1; Fig. 3 is a side elevation of the burner, the gas-chamber wall being partially cut away to show the interior, and Fig. 4 is a broken sectional perspective of the burner.

The following is a detailed description of the drawings.

A represents a plurality of metal channels which are positioned in parallelism but spaced apart. The spaces between adjacent channels are occupied by spacer bars indicated by B, B' and B'', three rows of bars being shown provided in each series, although two, or more than three rows of bars may be used, as may be desired. The rows of bars comprising each series of rows are assembled in staggered relation with their ends interlacing and the interlacing ends of the bars are pivoted together and to the lateral flanges of the adjacent channels, by means of the pivot rivets or bolts 1, which extend through alined holes in the bars and flanges, said holes being preferably loosely fitting to provide for expansion.

The manner of assembling the spacer bars forms the gas slots 2 which are thus disposed in parallel rows, the slots in one row being in staggered relation to the slots in the adjacent rows. The outer extremities of the end slots are closed by small spacer blocks 3 through which the rivets 1 pass.

C is the gas chamber, preferably formed by a convexed metal wall 4 whose top edges are brought up on the outside of the end channels A and turned over the flanges of the same, as shown 5 in Fig. 2, and riveted to said flanges. The ends of the

chamber C are closed by the vertical walls 6. D represents one or more fuel supply pipes, leading from a suitable gasifier or carbureter and discharging into the chamber C.

The interior or troughs of the channels A are preferably filled with asbestos wool as at 7, protecting the metal and assisting in the conservation of the heat.

10 To stiffen the channels and hold the same in proper alignment, I prefer to provide angle iron braces 8 which span the chamber C beneath the channels and are riveted to the bottoms of the same. Said braces may 15 be provided at more or less frequent intervals and at each end they are used for the attachment of the end walls 6 of the gas chamber.

10 The channel members support and stiffen 20 the burner structure, and the height of their flanges determine the depth of the gas slots which must be sufficient to give the proper velocity of travel of the gas. The asbestos protects the metal channels and 25 prevents the penetration of heat sufficient to cause preignition in the gas chamber. This elimination of heating sufficient to cause preignition is also contributed to by the velocity of the gas passing from the gas 30 chamber through the slots.

30 In operation the gasified fuel is supplied evenly throughout the burner surface, the depth of the slots, dictated by the height of the channel flanges and the bars, being sufficient 35 to give the necessary draft in the gas openings which prevents blow backs or the ignition of the fuel in the gas chamber.

30 The result is an even, uniformly distributed fire which is readily lit by the pilot 40 light or other ignition means, responding instantaneously, and thus insuring the prompt provision of steam pressure which is a cardinal necessity in steam-driven motor vehicles. Also the fuel supply may be 45 nicely regulated to produce the steam pressure desired without extinguishing the flame over a portion of the burner as is so frequently the case in many steam driven motor vehicles.

50 Although, for the sake of clearness, I have minutely described the embodiment of the principles of my invention illustrated in the drawings, I do not wish to limit myself thereby, but claim broadly—

55 1. A burner of the character described composed of a chamber adapted to receive the fuel in a gasified state and provided with a burner face composed of a plurality of impervious members in parallel and 60 spaced relation, and a plurality of spacer bars interposed between adjacent members in such a manner as to form gas slots, the said bars being secured in place at each end by pivotal attachment to provide flexibility 65 for expansion.

2. A burner of the character described composed of a chamber adapted to receive the fuel in a gasified state and provided with a burner face composed of a plurality of impervious members in parallel and spaced 70 relation, and a plurality of spacer bars interposed between adjacent members, said bars being assembled in staggered relation to form gas slots.

3. A burner of the character described 75 composed of a chamber adapted to receive the fuel in a gasified state and provided with a burner face composed of a plurality of impervious members in parallel and spaced 80 relation, and a plurality of spacer bars interposed between adjacent members, said bars being assembled in staggered relation, with interlacing ends, to form gas slots.

4. A burner of the character described 85 composed of a chamber adapted to receive the fuel in a gasified state and provided with a burner face composed of a plurality of impervious members in parallel and spaced 90 relation, and a plurality of spacer bars interposed between adjacent members, said bars being assembled in staggered relation, with interlacing ends, to form gas slots, and the ends of said bars being pivotally connected together.

5. A burner of the character described 95 composed of a chamber adapted to receive the fuel in a gasified state and provided with a burner face composed of a plurality of impervious members in parallel and spaced relation, and a plurality of spacer 100 bars interposed between adjacent members, said bars being assembled in staggered relation, with interlacing ends, to form gas slots, and the ends of said bars being pivotally connected together and to said members. 105

6. A burner of the character described composed of a chamber adapted to receive the fuel in a gasified state and provided with a burner face composed of a plurality of channel members disposed in parallel and spaced relation, and a plurality of spacer 110 bars mounted between adjacent channel members, said spacer bars being disposed in staggered relation so as to form gas slots.

7. A burner of the character described 115 composed of a chamber adapted to receive the fuel in a gasified state and provided with a burner face composed of a plurality of channel members disposed in parallel and spaced relation, and a plurality of spacer 120 bars mounted between adjacent channel members, said spacer bars being disposed in staggered relation, with interlacing ends, to form gas slots, and the ends of said bars being pivotally connected together.

8. A burner of the character described composed of a chamber adapted to receive the fuel in a gasified state and provided with a burner face composed of a plurality of channel members disposed in parallel and 130

spaced relation, and a plurality of spacer bars mounted between adjacent channel members, said spacer bars being disposed in staggered relation, with interlacing ends, 5 to form gas slots, and the ends of said bars being pivotally connected together and to said channel members.

9. A burner of the character described composed of a chamber adapted to receive 10 the fuel in a gasified state and provided with a burner face composed of a plurality of channel members disposed in parallel and

spaced relation, a filling of refractory material for said channel members, and spacer members interposed between adjacent channel members, said spacer members being in staggered relation with interlacing ends, and being supported in position by the pivotal 20 connection of their interlacing ends to said channel members.

Signed at Garfield, Ohio, this 9th day of November 1921.

DUNCAN MacDONALD.
